UNITED STATES PATENT OFFICE.

JOHN R. KARR AND CHARLES L. SHEPPARD, OF TRACY, CALIFORNIA.

HYDROCARBON BURNER.

1,407,283.

Specification of Letters Patent. Patented Feb. 21, 1922.

Application filed April 16, 1920. Serial No. 374,265.

To all whom it may concern:

Be it known that we, JOHN R. KARR and CHARLES L. SHEPPARD, citizens of the United States, residing at Tracy, in the 5 county of San Joaquin, State of California, have invented certain new and useful Improvements in Hydrocarbon Burners; and we do declare the following to be a full, clear, and exact description of the same, reference being had to the accompanying drawings, and to the characters of reference marked thereon, which form a part of this 10 application.

This invention relates to improvements in 15 hydrocarbon burners of a type adapted to be placed in ordinary domestic wood or coal burning ranges or stoves and particularly designed to use kerosene or gasoline and convert the same into gas before burning 20 the same.

The principal object of the invention is to produce a burner of this type in which simplicity of construction and efficiency of 25 operation are combined in the highest degree, which is so constructed that the tendency to leak at a vital point is reduced to a minimum.

We have found from experience that if a 30 burner of this type starts to leak and draws in air at any point above the line of fire, carbon will deposit in the burner passages in a very short time, leading to a rapid deterioration of the burner.

We have further observed however that 35 a leaky connection below the line of fire, somewhere in the vicinity of the raw fuel intake, while not desirable, is apparently harmless as far as being aid to the formation of carbon is concerned.

With this in mind we have so constructed 40 our burner that the same will have no connections of any kind above the line of fire, thereby insuring efficiency of operation and longevity of the burner.

Further, the burner is so made that the 45 gas passages will be perfectly smooth, thereby avoiding any tendency to form carbon deposits owing to any roughnesses or protuberances in the passages.

These objects we accomplish by means of 50 such structure and relative arrangement of parts as will fully appear by a perusal of the following specification and claims.

In the drawings similar characters of ref-

erence indicate corresponding parts in the 55 several views.

Fig. 1 is an elevational view of the burner showing the same positioned in the firebox of a range.

Fig. 2 is a vertical section of the burner. 60

Referring now more particularly to the characters of reference on the drawings, the numeral 1 denotes a substantially solid metal cylinder or base which serves as a fire plate and which has a horizontal rim or flange 2 65 adjacent its upper face overhanging the sides of the cylinder.

The under side of the base is provided with a tapped hole 3 to receive the threaded end 4 of a supply pipe 5, which supports 70 the burner and preferably rests on the firebox grate 6 of a range 7, the pipe 5 having a needle valve 8 interposed therein outside the range, to control the supply of fuel 75 through the pipe.

A transverse hole 9 is drilled through the base 1 below the rim 2 to communicate with the hole 3, its outer ends being tapped right and left hand respectively.

Extending above the base and in a vertical and diametrical plane therewith is an arched pipe 10 having a very small hole 11 on its under side directly above the center of the plate. This pipe passes below the level of the rim 2 of the base 1, the ends 85 thereof then being bent toward each other on a horizontal plane. One of such ends 12 is threaded with a right hand die and the other end 13 has a left hand thread, to enable such ends to fit into the correspondingly tapped hole 9. 90

This of course is easily accomplished by inserting the member 1 between the ends of the pipe by springing the same apart, and then turning either member relative to the 95 other in the proper direction.

We preferably employ an ordinary piece of iron pipe suitably bent to shape rather than a casting, both for cheapness of manufacture and ease of assembly and because it 100 is almost impossible to obtain a hollow casting of such small dimensions in which the inner face of the walls will be perfectly smooth and the walls themselves of equal thickness throughout. 105

In operation, the base 1 is first warmed by some suitable means and the fuel admitted through the pipe 5. As soon as it reaches the

hole 9, it is gasified and rises in the arch 10 on both sides, finally emerging thence through the hole 11 and blowing down onto the top of the member 1, where it may be ignited.

5 The flames will of course rise with the natural draft in the stove and will never pass below the top of the plate 1. In fact, even after the burner has been operating for 10 some time, the hand may be placed thereon in the vicinity of the pipe 5 without danger of burning the same.

15 The overhanging rim or flange 2 also serves to protect the screw connections of the pipe 10 with the base from any possible heat and thus insuring that the threads will not be subjected to undue expansion and contraction which would tend to cause leaks.

20 From the foregoing description it will be readily seen that we have produced such a device as substantially fulfills the object of the invention as set forth herein.

25 While this specification sets forth in detail the present and preferred construction of the device still in practice such deviations from such detail may be resorted to as do not form a departure from the spirit of the invention, as defined by the appended claims.

30 Having thus described our invention what we claim as new and useful and desire to secure by Letters Patent is:—

1. A hydrocarbon burner comprising a metal member serving as a burner plate, an oil supply pipe connected thereto, and a separate hollow arch-shaped member extending above said plate and spanning the same and provided with an orifice to discharge fuel gas onto the plate, the arch having threaded 35 connection at both ends with the plate below the line of the fire thereon and communicating with the supply pipe in said plate.

2. A hydrocarbon burner comprising a base serving as a burner plate, the same being provided with a tapped hole to receive an oil supply pipe and with a transversely drilled hole communicating therewith, the outer ends of the latter hole being tapped 40

right and left hand respectively and being on a horizontal plane considerably below the top of the plate, and a hollow arched pipe provided with an orifice adapted to discharge fuel gas onto the plate spanning the same and projecting thereabove, the lower ends of said arch being bent toward each other and threaded right and left hand respectively, whereby they may be secured in the tapped holes of the base.

3. A hydrocarbon burner comprising a metal member serving as a burner plate, an oil supply pipe connected thereto, and a separate hollow, continuous and smooth inner surfaced arch spanning the plate and provided with an orifice adapted to discharge fuel gas thereon and extending thereabove and connected thereto below the line of the fire on said plate, and having communication with the supply pipe there-through.

4. A hydrocarbon burner comprising a metal member serving as a burner plate, an oil supply pipe connected thereto, a hollow arch-shaped member extending above the plate and provided with an orifice adapted to discharge fuel gas thereonto, said arch having threaded connection with the sides of the plate below the top thereof and communicating with the supply pipe through the plate, and a rim on the plate overhanging the sides thereof above the threaded connections and shielding the latter.

5. A burner comprising a hollow base having an inlet; and a one-piece arch provided with a combustion orifice, the ends of the arch having oppositely threaded connection with opposite sides of the base, the arch being sufficiently resilient to permit the base to be introduced between the ends of the arch, the arch and the base being relatively movable to secure threaded connection between the ends of the arch and the base.

In testimony whereof we affix our signatures.

JOHN R. KARR.
CHARLES L. SHEPPARD.
